UNITED STATES PATENT OFFICE.

JOHN Q. SHERMAN, OF DAYTON, OHIO.

AUTOGRAPHIC REGISTER.

Application filed April 14, 1917. Serial No. 161,940.

To all whom it may concern:

Be it known that I, JOHN Q. SHERMAN, a citizen of the United States, and a resident of Dayton, in the county of Montgomery and State of Ohio, have invented certain new and useful Improvements in Autographic Registers, of which the following is a full, clear, and exact description, reference being had to the accompanying drawings, forming part of this specification.

My invention relates to autographic registers, the object of which is to deliver duplicate copies of printed or unprinted blanks filled out by handwriting made with a lead pencil or the like prior to the delivery of the slip. In machines of this character there have been developed in the past numerous ways of feeding the paper strips past the writing or tablet top portion to the tearing off point where the blanks are severed from the strips, among which are the feeding of the strips between revolving rolls held together by tension and the feeding of the strips by means of sprockets which engage substantial perforations along the marginal lines of the strips, and by successive engagement with the marginal series of holes constituting the perforations feed the paper along over the tablet top.

The difficulty encountered in the feeding of several strips of paper simultaneously between revolving rolls has been that the strips do not remain in registry with each other, so that the filling out of duplicate printed blanks becomes difficult. This difficulty is largely overcome by the sprocket feed, and if the sprocket feeding devices are properly constructed in combination with perforations in the paper of proper size and arrangement, there will be perfect registry of the strips at all times.

As can be readily understood, however, the roll feed type has one great advantage in being the simpler form of structure and in requiring no perforating of paper. It is my object in this invention to combine in one machine the advantages of the sprocket feed and the roll feed. I do not desire to feed the strips by means of marginal sprocket engaged perforations, but desire to use pins and perforations for the purpose only of aligning the strips, so far as this is possible.

In providing for the above purpose, the usual roll feed is used, with some slight points of difference which will be pointed

out. The pin aligning devices are arranged across the one feed roll transverse the path of the paper, and engage in perforations slightly larger than the pins, said perforations being located at one point only in each section of the strips. In the type of my invention which is the preferred one and the one shown in the drawings, the holes are so placed that they come near the head of the various forms or sections in the paper strips, so that when the separate pieces are torn off or severed, they will have the holes properly located for filing in binders or on filing pins or the like.

The above objects and advantages and other advantages which will be duly referred to are accomplished by that certain construction and arrangement of parts to be hereinafter more specifically pointed out and claimed.

In the drawings,

Figure 1 is a detail side elevation of the register, showing the upper corner thereof broken away.

Figure 2 is a top plan view of the parts shown in Figure 1.

Figure 3 is a sectional view of the rolls disassembled showing the feed of the paper.

Figure 4 is a detail side elevation of the tension roll elevating cam and finger.

Figure 5 is a longitudinal sectional view of a complete device constructed according to my invention.

On rods 21, journaled in the sides of the casing are the paper rolls A, B and C, the strips of paper a, b and c therefrom being drawn up over rollers 4^a, and over the tablet plate 2 to the feeding and aligning devices. In the top is mounted a roll 5, called the tension roll, under tension from spring 6. The roll 5 rides in slots 7 in the elevated portion 8 of the top 4.

For raising up the tension roll by hand there is provided a cam 9 pivoted to the side 100 of the casing 1, which cam is adapted to be pressed upwardly by a pin 10 carried on the lever 11. This pin 10 extends out far enough to be grasped in the fingers. No particular form of roll raising device is necessary, and the cam, lever and pin shown are merely given as exemplary of some sort of tension roll raising device.

The feed roll 12, which has in this instance a circumference slightly larger than the length of form which it is desired to feed by each operation, is mounted in the

usual manner beneath the tension roll. The feed roll is operated by means of a handle 13 which is stopped at the end of each operation by means of any usual spring pin 5 stop 14.

On both ends, preferably, of the feed roll is located a disk plate 15, provided with a cam 16, same being secured to the ends of the roll in any desired way so as to contact 10 with the tension roll. During most of the path of the rolls the disk plates do not affect their relation of tensioned contact, but near the end of the operation of the handle the raised portion or cam 16 of the plate 15 contacts with the tension roll and elevates it out of contact with the feed roll. This cam, for a purpose to be described, is of substantial length so as to keep the rolls out of contact just before the close of the feed of 20 each set of forms or slips.

The aligning feature of the register is provided by two pins 17, 17, set in the large feed roll transverse of its rotary movement. The pins are tapered to a blunt point, and 25 are set in a straight line across the roll in a position to be vertical when the handle has completed a revolution and the cams on the feed roll have removed the tension roll from contact position and let it back again. 30 This is the preferred position of the cams, the essential relation between them and the pins being that the tension should be released during the adjustment of the strips of paper, as will be described.

35 The paper strips *a*, *b* and *c* may be printed into forms and will have at the head of each form a pair of holes 18 which are preferably substantially larger than the base of the pins, and may be round or slightly 40 oblong. These holes are located a short distance behind the forward edge of the forms and thus can be used for filing in binders or the like. The spacing of the pins and holes is arranged for permitting the use of 45 the holes for such a filing of the severed slips. The holes also will be in like positions with relation to the printing on the forms so that when the holes are aligned, the printing will be aligned on the several 50 strips.

To give clearance to the pins 17, the tension roll is grooved at 19, 19, and the stripper and tablet top plates are notched out (Figure 2).

55 As so constructed, the paper is first placed in the machine by throwing up the tension roll by the hand lever, and inserting the duplicate strips *a*, *b* and *c* in registry between the rolls. The feed roll should be positioned 60 at the end of its stroke and thus the positioning pins will be about vertical. The holes in the paper are set over the pins, the tension roll permitted to come down over the feed roll, and the operation of the machine can be started. Each operation of the

handle will feed out one length of the paper for tearing off, which will bring the pins around to vertical again and in engagement with the holes of the next form.

As the pins come around with the feed 70 roll toward the end of the stroke, they will be thrust into the center of the holes in the duplicate strips. This is because the feed roll is larger in circumference than the length of form used in the paper. The cams 75 16 will then raise the tension roll and the paper will for the space, say of one inch be drawn along by the pins as they approach the vertical without the pressure of the tension roll on the paper strips, so that adjustment of the paper will be accomplished and the paper during the completion of the movement of the roll 12 will not be under the tension of the roll 5.

Since the paper is loosely held during 85 this time, without tension it will be possible for the duplicate strips to adjust themselves on the pins, thereby bringing them into alignment. The holes being larger than the pins permits of the adjustment of the paper 90 on the pins, since otherwise the pins would tear the paper in entering the holes. The strips can be slightly out of line and be drawn back into line by means of the pins 95 in this device.

At the start of the feed of the next strip, the pins will start the paper moving along with the feed rolls and, within an inch say, will release the papers altogether. There should not be any tension to speak of on the 100 paper strips while they are in engagement with the pins on the first half of their engagement with the paper, either from the source of supply of the paper or between the rolls of the feeding device. On the 105 second half of the engagement of the pins (i. e., the start of the feed) with the paper the friction between the rolls is not released. As stated above, the exact location and 110 length of the cams is the preferred form, and the machine would operate if the friction was relieved by the cams at the start as well as at the end of the feed.

It can be appreciated readily that the 115 above device aligns the paper by means of the pins without the necessity of marginal perforations, and without the necessity of providing feeding sprockets. The feed is the old roll feed without essential modification. The holes in the paper may be used 120 in many filing systems which is another advantage of the device. There is but one line of perforations for each feeding section of the paper and the loss in alignment in one revolution of a roll feed is not so much that 125 it cannot be easily taken up by some such structure as the one above described.

The various details of construction above described are intended as an example of the application of the principles of my inven- 130

tion, and not as the only manner in which the invention could be applied so far as its essential novelty is concerned.

Having thus described my invention, what I claim as new and desire to secure by Letters Patent, is:—

1. In a friction-roll manifolder provided with form strips having holes spaced apart the length of a form, a drive roll and a 10 operative driven roll for feeding forms nearly a form length at each feeding operation, pins on said drive roll for engaging form holes for feeding said forms the remaining 15 distance, and means for rendering the forms loosely held during the pin feed.
2. In a friction-roll manifolder provided with form strips having holes spaced apart the length of a form, a drive roll having a circumference substantially equal to a form 20 length, pins projecting from said drive roll in a single radial plane for engaging form holes at each revolution, a pressure roll co-operating with said drive roll for feeding forms, there being clearance in said pressure 25 roll for the passage of said pins, and means for rendering the forms loosely held during said passage of said pins.
3. In a friction-roll manifolder provided

with form strips having holes spaced apart the length of a form, a drive roll having a 30 circumference substantially equal to a form length, a pair of pins on said drive roll for engaging form holes at each revolution, a spring-pressed driven roll cooperating with said drive roll for feeding forms, there being 35 peripheral grooves in said driven roll for the passage of said pins, means for providing free form clearance between the rolls during said passage of said pins, and means adjacent the driven roll for stripping the 40 forms from said pins.

4. In a friction-roll manifolder provided with form strips having holes spaced apart the length of a form, a drive roll having a 45 circumference substantially equal to a form length, means for turning said drive roll a revolution at a time, a pair of pins on said drive roll normally engaging form holes, a driven roll having grooves into which said pins normally project, means for normally 50 preventing pressure on the forms between the rolls, and means for rendering the rolls cooperative throughout the greater part of a revolution of said drive roll.

JOHN Q. SHERMAN.
